WEFT-DETECTOR-WITHDRAWING MEANS FOR LOOMS.

Application filed May 13, 1926. Serial No. 108,934.

This invention relates to weft detectors for looms and it is the general object of the invention to provide improved means for withdrawing a detector of the side slip type to make clear the path of the incoming bobbin on the transferring pick.

In automatic looms of the multi-color type the magazine and weft detector are located on the same side of the loom and where the detector is of the type which projects into the shuttle from the side it is necessary to provide some means for pulling the feeler to one side as the full bobbin is placed in the shuttle. It is a more particular object of the invention to provide a detector of the side slip type having an extension to cooperate with an actuator for the replenishing mechanism, the actuator being formed to permit longitudinal adjustment of the detector along the bobbin.

It is a more specific object of the invention to provide a side slip weft detector formed of a piece of bent wire having the rear end roughened to engage the yarn and having the forward portion formed to cooperate with an actuating mechanism and withdrawing device, there being a resilient means to return the detector to normal position located between the roughened surface and the mechanism and device.

With these and other objects in view which will appear as the description proceeds, our invention resides in the combination and arrangement of parts hereinafter described and set forth in the claims.

In the accompanying drawings wherein we have shown a convenient embodiment of our invention,

Fig. 1 is a top plan view of our improved detector and associated parts showing the foot of the replenishing mechanism in section and the shuttle and lay in dotted lines in front center position,

Fig. 2 is a vertical section on line 2—2 of Fig. 1,

Fig. 3 is a front elevation on a reduced scale looking in the direction of arrow 3, Fig. 1,

Fig. 4 is an enlarged vertical section on line 4—4 of Fig. 1 looking in the direction of the arrows,

Fig. 5 is an enlarged fragmentary vertical section on line 5—5 of Fig. 3, omitting certain parts,

Fig. 6 is a section on line 6—6 of Fig. 5, and

Fig. 7 is a fragmentary detail view of a modified form of detector and associated actuator.

Referring particularly to Figs. 1, 2, and 3, it will be seen that we have provided a loom side 10, breast beam 11, and lay 12, the latter indicated in dotted lines. Secured to the loom side is a foot 13 of an inside frame 14 of a weft replenishing mechanism which may be of the form shown in Patent No. 1,030,748. Secured to the breast beam is an actuator stand 15 having a guide 16 in which is mounted for vertical reciprocation a block 17 to which is pivoted an actuator lever 18. The latter is connected by means of rod 19 shown in section in Fig. 1 to the weft replenishing mechanism (not shown) and operates when depressed to give indication of exhaustion of weft to initiate replenishment. A hub 20 formed with the stand 14 has extending therethrough a stud 21 on the outer end of which is pivotally mounted a transerrer arm 22 the rear portion of which is extended as at 23 to lie over and substantially parallel to the bobbin B in the shuttle S. The stand 15 is provided with a vertical slot 24 in which reciprocates the outer end of the actuator lever 18.

Under normal operation the block 17 receives a downward movement on each alternate or detecting beat of the lay and when sufficient weft for continued weaving is present the outer end of the actuator lever will be free to descend in slot 24 thus leaving rod 19 unmoved, but when there is insufficient yarn present the outer end of the actuator lever will be arrested by mechanism to be described and as block 17 descends rod 19 is depressed to give indication of weft exhaustion. The matter thus far described is of well-known construction and forms no part of the present invention.

In carrying our improvements into effect, we provide a stand 30 secured to the loom side 10 and bolt to the outer end thereof a bracket 31 having a horizontal slot 32. A second bracket 33 having a vertical slot 34 is held to the first named bracket by means of a bolt 35, the slots affording vertical and horizontal adjustment of the bracket 33. The upper end of the bracket is extended horizontally to provide a feeler bed 36 hav-

ing upstanding sides 37 and rear and front walls 38 and 39, respectively. Extending upwardly from the bed 36 is a boss 40 having an upstanding guide lug 41 extending through a removable cap 42 formed as indicated in Figs. 1 and 4, said cap being held in place by a screw 43 which passes into boss 40. The left hand wall 37 of the bracket 33 is provided with a notch 44 defined by said wall and a small projection 45 extending inwardly therefrom.

The right hand end of the stand 15 is provided with a horizontal slot 46 indicated in Figs. 1 and 6 and may be provided with a horizontally disposed U-shaped forwardly extending projection 47 communicating with the slot 46.

The detector element, which is of the side slip type, is formed preferably of a single piece of bent wire indicated at D and has the rear bobbin engaging end thereof provided with teeth 50 and has the other end thereof bent to extend rearwardly as at 51 into slot 46. The intermediate portions of the wire are provided with a rounded portion 52 at the right hand side of the detector D and a straight portion 53 designed to be held against the boss 40 by means of a coil spring 53'. Said spring has one end thereof secured to a small lug 54 cast integral with and projecting upwardly from the bed 36. Said spring extends around a second lug 55 also cast on the bed, the free end of said spring being received by a rearwardly curved portion 56 of the detector D. That portion of the wire which is received by the notch 44 is formed by an upward bend 57 in the wire as indicated in Fig. 4 and the wire is extended forwardly and then to the left as indicated at 58.

The transferrer arm 22 has downwardly extending spaced arms 59 between which extends a stud 60 and in order to provide for withdrawing the detector on transferring picks we provide a link 61 slotted as at 62 to receive the stud 60, the portion 58 of the detector extending through the rear end of the link. In order to permit forward movement of the upright portion 57 of the detector we provide the cap with a slot 63 extending forwardly from the notch 44 and cut an opening 64 in the cap which communicates with the slot 63 so that the upright portion 57 of the detector may be inserted in the slot.

Under normal conditions the parts are in the position indicated in full lines in Figs. 1 and 2, the end 51 of the detector lying normally under the actuator lever 18 and the teeth 50 being positioned to engage the yarn of the advancing shuttle, the detector being held in this position by spring 53'. So long as sufficient yarn is present the detector will be moved forwardly from the position indicated in Fig. 1 to withdraw the end 51 from beneath the actuator lever 18 permitting the

latter to descend without interruption, slipping movement to the side being prevented by entry of the teeth 50 into the yarn of the bobbin. When insufficient yarn remains on the bobbin, however, the latter will engage 70 the teeth 50 on the forward detecting beat and the detector D will swing angularly around the notch 44 as a pivot to the position indicated in dotted lines at 65 in Fig. 1 against the action of spring 53'. The end 51 75 of the detector is moved rearwardly a slight amount by this swinging of the detector and will therefore be under the actuator lever as the latter descends, with resultant depression of rod 19 to indicate weft exhaustion to the 80 replenishing mechanism.

On a subsequent beat of the lay when the shuttle which previously had given an indication of exhaustion arrives under the trans- 85 ferrer arm 23 the latter will descend by mechanism not shown but well understood in the art and set forth in the aforesaid patent, said movement of the transferrer arm moving the link 61 to the position indicated in dotted lines in Fig. 2. This forward 90 movement of the link will move the upright portion 57 of the wire forwardly in slot 63, the curved rearwardly extending portion 66 of the detector being guided along an edge 67 of the rear wall 38 of the bracket 33 and the rounded portion 52 being guided by the right hand wall 37, as will be understood from an inspection of Fig. 4. This forward movement of the detector D accomplishes two necessary results, namely, the rear toothed 95 end of the detector is moved out of the path of the incoming bobbin and the end 52 is moved forwardly from under actuator lever 18. The incoming bobbin will therefore not damage the detector and the lever 100 105 110 115 120 125 130 135 140 145 150 155 160 165 170 175 180 185 190 195 198 200 205 210 215 220 225 230 235 240 245 250 that the spring 53' being bent upon itself can be accommodated in a comparatively small space and yet be of sufficient length to permit the forward movement of the detector necessary on transferring beats of the loom. It is to be understood that the side slipping movement of the detector gives the controller end 51 a rearward movement and for this reason the said end may lie forwardly of the actuator lever 18 under normal conditions as indicated at 70 in Fig. 7, reliance being had upon the angular movement of the detector about the notch 44 as a center to move said controller 70 under the actuator when exhaustion of weft is indicated.

Having thus described our invention it will be apparent that changes and modifications may be made therein by those skilled in the art without departing from the spirit and scope of the invention, and we do not wish to be limited to the details herein disclosed, but what we claim is:

1. In a weft detector for looms having a yarn surface to be detected and an actuator to effect a change in the loom, a support, and a detector mounted on the support, said detector being in the form of a bent wire and having a yarn engaging surface at one end to detect the condition of yarn and having also a controller portion at the other end to be moved under the actuator, said detector being further provided with an intermediate portion serving as a pivot to be received by the support, and resilient means to hold the detector in normal position, said detector at substantial exhaustion of weft having an angular movement about the pivot thereof and along the bobbin to move the controller end thereof under the actuator.

2. In a weft detector for looms having a yarn surface to be detected and an actuator to effect a change in the loom, a support, and a detector formed of a single piece of wire, said detector having at one end a roughened part to cooperate with the surface to be detected and having at the other end a controller for the actuator, said wire intermediate the ends thereof being bent to form a pivot held normally in a recess in the support, the roughened part sliding along an exhausted bobbin to move the wire angularly about the pivot therefor to move the controller end under the actuator.

3. In a weft detector for looms having a yarn surface to be detected and an actuator to effect a change in the loom, a support, a detector formed of a single piece of wire, said detector having at one end a roughened part to cooperate with the surface to be detected and having at the other end a controller for the actuator, said wire intermediate the ends thereof being bent to form a pivot held normally in a recess in the support, the roughened part sliding along an

exhausted bobbin to move the wire angularly about the pivot therefor to move the controller end under the actuator, and resilient means to hold said bent end in the recess and said detector in normal position.

4. In a weft detector for looms having a yarn surface to be detected and an actuator to effect a change in the loom, a support, a detector formed of a single piece of wire, said detector having at one end a roughened part to cooperate with the surface to be detected and having at the other end a controller for the actuator, said wire intermediate the ends thereof being bent to form a pivot held normally in a recess in the support, the roughened part sliding along an exhausted bobbin to move the wire angularly about the pivot therefor to move the controller end under the actuator, resilient means to hold said bent end in the recess and said detector in normal position, and means acting on the wire between the controller and pivot portions thereof to withdraw the detector on transferring beats of the loom.

5. In a weft detector for looms having a yarn surface to be detected and an actuator to effect a change in the loom, a support, a detector formed of a single piece of wire, said detector having at one end a roughened part to cooperate with the surface to be detected and having at the other end a controller for the actuator, said wire intermediate the ends thereof being bent to form a pivot held normally in a recess in the support, the roughened part sliding along an exhausted bobbin to move the wire angularly about the pivot therefor to move the controller end under the actuator, resilient means to hold said bent end in the recess and said detector in normal position, and a guide for said actuator and controller, said guide having a slot for the controller extending substantially parallel to the shuttle whereby the controller may assume a plurality of positions under the actuator.

6. In a weft detector for looms having a yarn surface to be detected and an actuator to effect a change in the loom, a support, a detector formed of a single piece of wire, said detector having at one end a roughened part to cooperate with the surface to be detected and having at the other end a controller for the actuator, said wire intermediate the ends thereof being bent to form a pivot held normally in a recess in the support, the roughened part sliding along an exhausted bobbin to move the wire angularly about the pivot therefor to move the controller end under the actuator, and resilient means to hold said bent end in the recess and said detector in normal position, said resilient means being in the form of a coil spring bent on itself and having one end held with respect to the support and having the other end attached to the wire.

and having the intermediate portions extending around another portion of the support.

7. In a weft detector for looms having a surface to be detected and an actuator to effect a change in the loom, a support, a detector mounted on the support in the form of a bent wire having a rearwardly extending yarn engaging detector tip on one end 5 and having the other end formed as a controller to be moved under the actuator, the intermediate portion of the detector being formed as a pivot to be received by a notch in the support, a cap for the support having 10 a slot therein through which the pivot portion of the detector extends, and means to withdraw the detector on transferring beats of the loom to move the detector tip out of the path of the incoming shuttle and the 15 controller end from under the actuator, the pivot portion of the detector moving away from the notch in the support and in the slot in the cover.

8. In a side slip weft detector for looms 20 having a surface to be detected and a regu-

larly moving actuator, a support having a pivotal notch formed therein, a weft detector formed of a wire having a rearwardly extending detector tip on one end and having on the other end a controller to move 25 under the actuator at indication of weft exhaustion, said detector having a portion to cooperate with the pivoted notch of the support, and resilient means to hold the detector in normal rearward position, said resilient means comprising a spring attached to the portion of the detector between the detector tip and the pivot portion of the detector, said spring being attached to a portion 30 of the support and extending around another portion of said support to increase the length of the spring, and means to withdraw the detector on the transferring beat 35 of the loom, said spring expanding as the detector is withdrawn.

In testimony whereof we have hereunto affixed our signatures.

HAROLD L. BLANCHARD.
